UNITED STATES PATENT OFFICE

RICHARD V. SPENCER, OF LOS ANGELES, CALIFORNIA

DESIGN FOR A COMBINED TRAFFIC SIGNAL AND LAMP POST

Application filed July 31, 1929. Serial No. 32,255. Term of patent 7 years.

To all whom it may concern:

Be it known that I, RICHARD V. SPENCER, a citizen of the United States, residing at Los Angeles, in the county of Los Angeles and State of California, have invented a new, original, and ornamental Design for a Combined Traffic Signal and Lamp Post, of which the following is a specification, reference being had to the accompanying drawing, forming part thereof.

Figure 1 is an elevation of a combined traffic signal and lamp post, showing my new design.

Figure 2 is an elevation of the same taken at right angles of Figure 1.

I claim:

The ornamental design for a combined traffic signal and lamp post substantially as shown.

RICHARD V. SPENCER.
